UNITED STATES PATENT OFFICE.

NATHAN RAVICH, OF PITTSBURG, PENNSYLVANIA.

OVERALLS OR NETHER GARMENT.

SPECIFICATION forming part of Letters Patent No. 724,204, dated March 31, 1903.

Application filed April 19, 1901. Serial No. 56,595. (No model.)

To all whom it may concern:

Be it known that I, NATHAN RAVICH, a citizen of the United States of America, residing at Pittsburg, in the county of Allegheny and 5 State of Pennsylvania, have invented certain new and useful Improvements in Overalls or Nether Garments; and I do hereby declare the following to be a full, clear, and exact description thereof, reference being had to the 10 accompanying drawings, which form a part of this specification.

This invention relates to certain new and useful improvements in overalls or nether garments, and more particularly to the class of 15 garments in which a seam extends downward on the outside of the leg.

The object of this invention is to economize in the cutting, so that the two leg portions of the garment may be laid side by side adjacent to each other and cut from the same width. These leg portions are cut their full length and the two are then secured together, each pattern or leg portion being cut at a bias at the crotch-piece of the pattern, whereby 25 the two patterns or leg portions will match neatly together in the finished garment.

In the accompanying illustration, Figure 1 is a detail perspective view of my improved garment. Fig. 2 is a detail plan view of one 30 of the patterns or leg portions. Fig. 3 is a detail perspective view of one of the fastening-buckles carried by the supporting-straps.

In the accompanying drawings, 1 indicates the legs of the garment, the seam 2 of which 35 is along the outside thereof. These legs 1, together with the body portion of the garment, are formed from a pattern which is shown in detail in Fig. 2 of the drawings. This pattern is cut with a flap 3 along one edge, and 40 at its upper end is cut away for some distance into the same, the edge 4 of the cut-away portion being on a vertical line to a point near the lower end of the cut-away portion and the edge 5 of said cut-away portion being cut on 45 a bias and terminating with the lower end of the edge 4. When this pattern has been cut, as shown in detail in Fig. 2, the part 6 thereof is folded over onto the part 7 and stitched along the edges to form the seam 2. The flap 50 3 is tucked in against the inner face of the

part 6 and sewed thereto to form the edge for the pocket 8, the latter being formed by stitching the part 6 to the part 7, as shown at 9 in Fig. 1. The two patterns are secured together as at 10, and bound, in addition to 55 this securing means, by a reinforcing-strap 11. The supporting-straps 12 are preferably secured at their lower end between this reinforcing-strap 11 and the material of which the overalls are formed, and these straps cross 60 each other and carry suitable buckles 14 to engage with buttons 15 on the front of the overalls. When hip-pockets are desired, these may be of the patch or box form, in which a piece of cloth or fabric is cut out the shape 65 of the pocket and stitched to the garment, as at 16. I may also attach to the front of the garment a supplemental pocket 17, which is secured thereto in the same manner as the hip-pocket 16. The garment is suitably fastened at the front in any desired manner. In the construction of such garment it will be observed that the two patterns are exactly 70 similar and but little labor is required to complete a garment.

Having fully described my invention, what I claim as new, and desire to secure by Letters Patent, is—

A pair of overalls comprised of two sections of the same pattern, each section having a 80 portion adapted to fold over to form a leg for said overalls, a pocket-flap made integral with the outer edge thereof, an extended portion above said leg-section forming an apron for the garment, said extended portion sloping 85 inwardly along its outer edge, and having a vertical inner edge, with an inwardly-curved end, an outwardly-curved cut-away portion extending from the base of the vertical edge of said apron-forming piece, said two sections 90 adapted to be secured by overlapping the edges of the apron and cut-away portion of each section, substantially as described.

In testimony whereof I have hereunto affixed my signature in the presence of two subscribing witnesses.

NATHAN RAVICH.
